(57) CLAIM

The ornamental design for an article of furniture, as shown and described.

DESCRIPTION

FIG. 1 is a perspective, front view of a first embodiment of an article of furniture;

FIG. 2 is a plan view thereof;

FIG. 3 is a rear view thereof;

FIG. 4 is a right side view thereof;

FIG. 5 is a front view thereof;

FIG. 6 is a left side view thereof;

FIG. 7 is a perspective, rear view thereof;

FIG. 8 is a sectional view taken along lines A-A in each of FIGS. 1, 7, 9, and 15 of the drawings;

FIG. 9 is a perspective, front view of a second embodiment of an article of furniture;

FIG. 10 is a plan view thereof;

FIG. 11 is a rear view thereof;

FIG. 12 is a right side view thereof;

FIG. 13 is a front view thereof;

FIG. 14 is a left side view thereof; and,

FIG. 15 is a perspective, rear view thereof.

The broken lines illustrate portions of the article of furniture that form no part of the claimed design.

1 Claim, 2 Drawing Sheets
